CRANE CAB

Thomas L. Hammond, Chicago, Ill., assignor to
Whiting Corporation, Harvey, Ill., a corpora-
tion of Illinois

Application February 3, 1949, Serial No. 662

Term of patent 14 years

(Cl. D41—1)

To all whom it may concern:

Be it known that I, Thomas L. Hammond, a citizen of the United States of America, and a resident of the city of Chicago, county of Cook, and State of Illinois, have invented a new, original, and ornamental Design for a Crane Cab, of which the following is a specification, reference being had to the accompanying drawing, forming a part thereof.

In the drawing:

Fig. 1 is a perspective view of a crane cab, showing my new design;

Fig. 2 is a side elevational view thereof on a slightly reduced scale; and

Fig. 3 is a front elevational view of Fig. 2.

I claim:

The ornamental design for a crane cab, sub-
stantially as shown.

THOMAS L. HAMMOND.
